UNITED STATES PATENT OFFICE.

FRANK J. LEHR, OF ROCHESTER, NEW YORK, ASSIGNOR TO STECHER LITHOGRAPHIC COMPANY, OF ROCHESTER, NEW YORK, A CORPORATION OF NEW YORK.

PRINTING-PRESS.

1,351,175.

Specification of Letters Patent. Patented Aug. 31, 1920.

Application filed August 27, 1917. Serial No. 188,347.

To all whom it may concern:

Be it known that I, FRANK J. LEHR, of Rochester, in the county of Monroe and State of New York, have invented certain 5 new and useful Improvements in Printing-Presses; and I do hereby declare the following to be a full, clear, and exact description of the same, reference being had to the accompanying drawings, forming a part of 10 this specification, and to the reference-numerals thereon.

My invention relates to a printing press and particularly to a shifting mechanism for the press cylinders and has for its object 15 to automatically effect the separation of the impression and printing, or form, cylinders by the use of electric circuits of relatively high and low voltage currents in the absence of a sheet from the grippers during 20 the feeding process. Another object of the invention is to effect the closing of a relatively low voltage electric circuit in which is arranged a magnet adapted to effect the closing of a relatively high voltage circuit, 25 insulated from the press, and serving to operate means for controlling the shifting of one of the press cylinders by the operation of another in absence of a sheet from the grippers thereof. To these and other 30 ends the invention consists in certain improvements and combinations of parts, all as will be hereinafter more fully described, the novel features being pointed out in the claims at the end of the specification.

35 In the drawings:

Figure 1 is a side elevation illustrating one embodiment of the invention with the cylinders shown in normal position, and

Fig. 2 is a similar view illustrating the 40 position of the cylinder shifting mechanism after the electric circuits have been closed to effect operation of the same.

Similar reference characters throughout the drawings indicate similar parts.

45 In printing and lithographic presses it is necessary when a sheet has been missed in the feeding to at once separate the cylinders. If this were not done an impression would be delivered from the printing surface to the impression cylinder, and the succeeding sheet would thereby have an im-

pression in reverse print upon the back as well as the regular impression on the face. It is, therefore, necessary to provide means for automatically separating the cylinders 55 in cases where sheets are missed in the feeding process. Heretofore in electrical devices provided for this purpose the trouble experienced has been that the strength of the current required to perform the necessary operations has been greater than the operator could stand, in cases where the current leaked through the press, the result being that the workmen often become violently shocked while manipulating the machine. 60 It is to overcome these and other disadvantages of the present day shifting mechanisms that the invention set forth herein is intended to accomplish.

In the embodiment shown, 1 represents a 70 portion of the frame of a printing-press upon which the cylinders 2 and 3 are mounted, comprising respectively the impression and plate, or printing cylinders. A plurality of grippers 4 are mounted on the shaft 5 of the impression cylinder at equal distances apart, the points of the grippers when closed serving to hold the sheets upon the contacts 6 supported by the insulation 7 on the bars 8. The contact 6 is connected with the surface 9 of the cylinder 2 by means of the wire 10, while during rotation of the cylinder said surface engages the contact 11 of the frame, as shown in Fig. 2, thereby completing the circuit through conductor 12, 75 battery 13, conductor 14, magnet 16 and conductor 17. Thus it will be seen that the gripper 4 and contact 6 form the means by which the absence of the sheets is detected. If there is no paper between these points 80 when the gripper descends the magnet 16 will be energized to draw the armature 18 away from the insulated point 19, against the action of the spring 20, and into engagement with the contact 21, thereby closing the 85 main circuit, which is the trip controlling circuit, through conductors 22 and 23, magnet 24 and conductor 25.

The plate, or operating cylinder, 3 is provided with an eccentric bearing 26, to the 100 arm of which is pivotally connected the downwardly extending rod 27 arranged to

project loosely through the guide 28 on the press frame 1. The rod is held in normal position as shown in Fig. 1, by the compression spring 29 mounted between the guide 28 and adjustable stop 30 on the rod. The rod carries an adjustable collar, or projection, 31 which is arranged to be engaged at the proper time by the bell crank arm 32, after the arm 33 has been attracted by the magnet 24 when the main, or high voltage, circuit is closed through the armature 18 under the action of the magnet 16. The bell crank is pivoted upon the lever 34, which is pivotally mounted upon the press frame at 35, said lever being held in normal position by the spring 36 having one end connected with the rearwardly extending arm 37 and the other with the stop 38 on the frame. The lever is provided with a lug, or projection 39, extending into the notch 40 of the bell crank constituting stops to limit its up and down movement. When the cylinder 2 is revolving in the direction indicated by the arrow the cam 41 will engage the roller 42 of the lever 34 and depress the latter, and if the paper is between the gripper 4 and contact 6 the arm 32 of the bell crank will escape the projection 31, thus allowing the rod 27 to remain at normal position. However, in the absence of a sheet between the gripper 4 and contact 6 the low voltage battery circuit will serve to effect a closing of the main, or high voltage, circuit by means of the magnet 16 and armature 18, thereby causing the energization of the magnet 24, which will attract the arm 33 of the bell crank, thus placing the arm 32 in position to engage the collar 31 so that the rod 27 will be forced down by the lever 34 when the latter is operated by the cam 41. This will effect, by means of the eccentric bearing 26, a movement of the printing cylinder 3 in a direction away from the impression cylinder 2, as indicated by Fig. 2, in which position it will remain as long as the battery circuit is closed. By this means it will be seen that a relatively high voltage circuit may be used for effecting the operation of the cylinder trip mechanism without danger of throwing the current into the press and injuring the operator, while a current of relatively low voltage may be used both for detecting the absence of a sheet from the grippers and for automatically closing the high voltage circuit which controls the tripping mechanism.

I claim as my invention:

1. In a printing press, the combination of a frame, an impression cylinder rotatively mounted therein and adapted to receive a work sheet, a rotatable plate cylinder normally in contact with said impression cylinder, a rock arm pivoted to the frame, means actuated by said impression cylinder for rocking said arm, and an electrically controlled bell crank pivoted to said rock arm

and adapted to separate said cylinders in the absence of a work sheet on the impression cylinder.

2. In a printing press, the combination of a frame, an impression cylinder rotatively mounted therein and adapted to receive a work sheet, a plate cylinder coöperating with said impression cylinder, a rod connected with said plate cylinder for shifting the latter away from the impression cylinder, a projection on said rod, a bell crank having an arm normally out of position to engage said projection but movable to a position to engage said projection and shift said cylinder, and electric means comprising a circuit adapted to be closed in the absence of a sheet from the impression cylinder for moving said bell crank into position to engage said projection. 70 75 80

3. In a printing press, the combination with impression and plate cylinders adapted to operate upon a work sheet, of automatic means for separating the cylinders in the absence of a work sheet, said means comprising grippers and complementary contacts on said impression cylinder adapted to engage a work sheet, an electric circuit comprising a relay adapted to operate when the grippers engage said complementary contact in the absence of a work sheet, a source of electric current for said circuit of such low tension as to be inappreciable to the human body, a second electric circuit of relatively higher tension actuated by said first circuit and mechanism for separating the impression and plate cylinders when said second circuit is energized. 90 95 100

4. In a printing press the combination with a frame of impression and plate cylinders, automatic means for separating the cylinders in the absence of a work sheet, said means comprising an eccentric bearing for said plate cylinder, a slidable rod attached thereto for moving the same, a projection on said rod, a lever pivoted to said frame, a cam rotatable with said impression cylinder, a roller on said lever for coöperation with said cam, a bell crank lever pivoted to one end of the first mentioned lever, normally free from coöperation with said projection on said rod, and provided with a notch adjacent the pivot, a projecting lug on said lever in coöperation with said notch to limit the pivotal movement of said bell crank lever and an electric magnet fixed relative to said frame and adapted to engage one arm of said bell crank lever when energized, the other arm of said bell crank lever being adapted to engage the projection on said rod to move the same when said magnet is energized. 105 110 115 120 125

5. In a printing press the combination with a frame of impression and plate cylinders adapted to operate upon a work sheet, automatic means for separating the cylinders 130

ders in the absence of a work sheet, said means comprising eccentric bearings for said plate cylinder, a slideable rod attached thereto for moving the same, a projection on said 5 rod, a lever pivoted to said frame, a cam rotatable on said impression cylinder, a roller on said lever in coöperation with said cam and an arm pivotally attached to said

lever and normally not engaging said projection on said rod, means for moving said arm into coöperation with said projection to move said rod and stops on said lever and arm to limit the pivotal movement of said arm on the lever.

FRANK J. LEHR.
